CLAIM

The ornamental design for a pressure detector, as shown and
described.

DESCRIPTION

FIG. 1 is a side elevational view of a pressure detector showing
my new design;

FIG. 2 is a side elevational view of a pressure detector turned
90° from that of FIG. 1;

FIG. 3 is a rear view thereof;

FIG. 4 is a front view thereof; and,

FIG. 5 is a front, right side perspective view thereof.

The broken line portions of the figure drawings is included to
show environmental subject matter only and forms no part of
the covered design.
